SOAPMAKING PROCESS

George B. Bradshaw, Wilmington, Del.

Application June 29, 1945, Serial No. 602,227

4 Claims. (Cl. 260—418)

1

This invention relates to the manufacture of soap. More particularly, this invention deals with that process of making soap wherein natural fats, consisting essentially of glycerine esters of higher fatty acids, are first converted into lower alkyl esters of said higher fatty acids, say the methyl, ethyl, propyl or butyl esters, and the latter are then saponified with caustic alkali, liberating respectively methyl, ethyl, propyl, or butyl alcohol.

According to my invention fatty materials, predominantly lower alkyl esters of fatty acids, are continuously saponified at a temperature of about 105° C. under agitation and pressure and, after reducing the vapor pressure by heat interchange and by addition of cold liquor, separated into neat soap and nigre under atmospheric pressure conditions.

The ordinary soap boiling process involving a recovery of glycerine and a purification of the soap by the separation of a neat soap and a nigre is an operation requiring 4 to 14 days and the consumption of considerable energy in the form of steam. The saponification in itself is an exothermic reaction. There is enough heat set free to bring the starting materials to the reacting temperature. This could be an ideal situation for a continuous process heat exchange operation in which the heat of reaction would be used to heat the starting materials. However the diversity and number of time consuming steps in soap boiling of glycerides prevent it from being amenable to such a rational process. In soap boiling the mass of material under treatment is agitated by live steam while in a dispersible condition which is obtained by the presence of enough electrolyte to produce a partial salting out or graining effect. The saponification and the removal of the glycerine occur in stages generally involving delays for slow gravity separation of liquor from grained soap or curd. Finally the electrolyte concentration is lowered by sedimentation with draining off of free liquor and by introduction of water so that a portion of the soap, with the aid of the boiling employed, is dissolved. The soap is then allowed to stand with as little heat loss as possible until it separates into a neat soap and a nigre. The nigre contains most of the impurities. The neat soap has an especial brightness not easily obtained by any other procedure, but it contains about 1/2% salt.

The various difficulties just outlined which prevent using a rational continuous process for saponification to produce neat soap are overcome by my invention. The manufacture of soap from lower alkyl esters of fatty acids instead of from glycerides requires no steps for removing glycerine. The previous removal of the glycerine has also removed most of the impurities from the fat. However the lower alcohol will still be pres-

ent. It is useful during the saponification because it increases the diffusivity and dispersivity of the charge. Practically no salt need be present. The alcohol, however, because of its low boiling point causes foam which precludes saponification in an open boiling operation or a separation in the manner of the previous art over a nigre.

According to my invention, the saponification, for example, of the methyl esters of fatty acids is carried out continuously under agitation and pressure, under such conditions that the mass is continually reactive and easily agitated and is flowable. Also, directly after saponification it can be fitted or finished by the continuous addition of water or very dilute electrolyte which at the same time brings the temperature of the mass below the foaming point but not below a suitable temperature for separation into neat soap and nigre. Thus an entirely new result is obtained, that is a separation of neat soap and nigre without a previous boiling operation in the fitting step. The alcohol which has acted as an adjunct is removed in any subsequent drying operation.

An outline description of a soap production according to my invention now follows. The finished or fitted soap is discharged continuously from the last of a series of agitated closed reactors to heat insulated settling vessels where the soap can separate into two layers with a temperature loss of only 5 to 10° C. After settling the bright upper layer of neat soap is drawn off and made into merchantable soap in one of the usual ways or as discussed later in this specification. The lower layer or nigre is grained, and settled. The lye containing methyl alcohol is drained off and the soap fitted and allowed to separate to a neat soap and a second nigre. The nigre and lyes from this operation are worked up for their values. The neat soap from this second nigre is boiled up with about an equal weight of water or very dilute brine depending on conditions and fed continuously to the reactors in admixture with hot methyl esters. These methyl esters have been heated to about 95° C. preferably by heat interchange as a result of removing the heat of reaction of the saponification. The esters may be the heat exchange medium or be heated indirectly by the medium. It is only necessary that under the heat conditions existing the starting materials are hot enough so that the reaction starts and ends quickly enough for the time of passage and that the reaction occurs between about 100 to 120° C. This hot material is fed continuously seriatim to a series of, say four, agitated pressure reactors. At the same time the proportioned amount of caustic soda is fed to the reactors but distributively, in stages, that is, assuming the main

2

reaction is carried out in three reactors, then about one third of the caustic soda is fed continuously to each reactor. The time of passage through the reactors is governed by the speed of reaction and the efficiency of the heat transfer. To the fourth or last reactor is continuously added the amount of water or dilute electrolyte needed to fit the soap. This last addition can be such as to prepare the soap for separation into neat soap and nigre with about 88% of the total soap as neat soap. It also cools the mass to such a point that undue foaming does not occur on discharge of the material to atmospheric pressure for the neat soap and nigre step.

A plant suitable for carrying out the previously described process is shown diagrammatically in the accompanying drawing. Referring to the drawing, the tank 1 is the storage tank for methyl esters. Tank 2 is storage for caustic soda solution. Feeder pumps 3, 4, and 5 are for hot methyl esters, for hot diluted neat soap from nigre and for caustic soda solution respectively. These pumps feed the materials continuously in proportioned amounts to the agitated pressure reactors 6, 7, 8, and 9. These reactors are connected in series so that the discharge from the first feeds the second and so on. Preferably these machines are constructed similarly to a standard jacketed soap crutcher with the feed into the center draft tube except they are closed in for pressure work. The agitation forces the material down through the center draft tube and up the sides. The discharge outlet is at the top. The center tunnel or draft tube is double walled and the machines are jacketed for circulation of the heat transfer medium. Between reactors 8 and 9 is a throttle 23 for maintaining the desired pressure in 6, 7 and 8. Insulated tanks capable each of holding 24 hours' production are 10¹, 10², 10³, 10⁴, and 10⁵. These can be of the usual type for soap boiling and separation into neat soap and nigre. Heat is removed from the reactors by the circulation of a heat transfer medium through their jackets preferably entering first the jackets of reactor 9. This medium after leaving the jackets of reactor 6 passes through coils in the methyl ester storage tank 1 and then returns to jackets of reactor 9. Alternatively the methyl esters may be heated directly by passing from tank 1 to the jackets of reactors 9, 8, 7, and 6 in series and then be fed by pump 3 and pipe 12 to the series of reactors commencing with 6. Caustic soda solution is fed through pipe 24, and partitioning valves 25, 26, and 27 to the feed pipes 18, 19 and 20 of reactors 6, 7, and 8. Water or electrolyte solution is continuously fed proportionally through 23 to center feed of reactor 9.

Example 1.—An operation for production of about 100,000 pounds per day of neat soap is now described. For this operation methyl esters having a saponification value of 190.8 were used. The materials consumed each hour to feed the reactors were:

	Pounds
Methyl esters, temperature 95° C. (2800 lbs. fatty acids)	2940
Caustic soda, 45%, temp. 25° C. equals 6% excess	945
Dilute neat soap from nigre, temp. 95° C. (contains 0.7% salt and 280 lbs. fatty acids total)	900
5% salt solution, temp. 25° C.	790

described above. The reactors were each of about 600 gallons capacity. To start the operation the methyl esters were heated to 95° C. in the storage tank 1 and then flowed through the jackets of the reactors before being fed by pump 3. After starting they were kept heated to 95° C. by the heat taken up in passing through the jackets. The electrolyte solution fed continuously through pipe 23 to reactor 9 was a 5% salt solution. The strength of this solution and the amount used will vary with the fats employed and the percentage of the total fatty acids desired in the nigre. The control is well known to those skilled in the art and is clearly explained for example in Wigner's "Manufacture of Soap." The amount can be varied by varying the dilution of the returned neat from nigre soap. Also the amount needed depends on the heat balance of the system. It is necessary to bring the temperature of the fitted soap below the point at which it will foam out of the settlers. In this case the material discharged from reactor 9 was at a temperature of 85° C. and on standing 24 hours was found separated to a neat soap and a nigre. The neat soap was 62.27% fatty acids and contained 87.92% of the total fatty acids and the nigre 12.08%. The nigre for each day's run was grained by addition of brine in the usual way and fitted so that 24.73% of its fatty acids went to a second nigre. This 24.73% amounted to 92 pounds of each hour's consumption of 2800 lbs. fatty acids or 3.3%. The neat soap from the new nigre was boiled up with an equal amount of 1% brine and returned at the rate of 900 lbs. diluted hot material per hour. The percentage of salt in the material passing through the first three reactors was less than 0.15% but enough to guarantee the necessary fluidity. This means a soap exceedingly low in salt can be made if the original fitting is done with dilute caustic soda solution instead of brine. In such case the excess caustic in the neat soap can be neutralized in the crutchers ahead of the chilling rolls by addition of castor oil fatty acids or methyl stearate or similar fatty material. In 45 the saponification just described the heat balance was about as follows:

	Calories
Heat from reaction,	
2940 lbs. = 1333 kilos $\times$ 75	100,000
50 Cool dilute soap from nigre 10° C.	
c. = 0.8	3,275
	103,275
55 Loss by radiation, 5,500 Cal. per reactor	22,000
	81,275
Net heat to dispose of	81,275
This was done as follows:	
	Calories
60 Raise 1333 kgs. methyl esters from 25° C. to 85° C., 1,333 $\times$ 60 $\times$ 5	40,000
Raise 430 kgs. caustic soda sol. from 25° C. to 85° C., 430 $\times$ 60 $\times$ 8	20,640
Raise 360 kgs. 5% brine from 25° C. to 85° C., 360 $\times$ 60 $\times$ 95	20,520
	81,160

The temperature in reactors 6, 7 and 8 ran from about 105° to 115° C. The pressure was maintained equivalent to 115° C. *Example II.*—An operation for about 8900 lbs. per hour of neat soap made from an 80% tallow 20% coconut oil composition is now described. For a 24 hour operation 123,100 lbs. crude tallow containing 12% fatty acids in free state was

ester interchanged using a special acid catalyst to produce 120,214 lbs. oil containing 86% methyl esters, 8% glycerides and 6% free fatty acids. 29,800 lbs. refined coconut oil also was ester interchanged but using an alkaline catalyst to produce 29,530 lbs. oil containing 97½% methyl esters and 2½% glycerides. The combined esters totaling 149,744 lbs. had a saponification value of 204. The theoretical amount of caustic soda needed was 21,780 lbs. There was used 51,500 lbs. of 45% solution that is 6% excess. The materials consumed each hour to feed the reactors were:

	Pounds
Methyl esters, temperature 95° C. (5,940 lbs. fatty acids)	6240
Caustic soda, 45% temp. 25° C. equals 6% excess	2146
Diluted neat soap from nigre, temp. 95° C. (594 fatty acids)	1815
5% salt solution, temp. 25° C.	1420

There were four reactors each of 1200 gallons capacity. The procedure was practically the same as in Example I. The neat soap was 62.35% fatty acids and contained 86.8% of the total fatty acids in the operation for separation of neat soap and nigre. From the nigre not returned to the operation and other losses there was a total loss of 5.4% of the fats charged. Of this loss 75% was recovered as fatty acids. There was about 0.17% salt in the material passing through the first three reactors. The average temperature of the first three reactors was 110° C.

Preferred procedures have been detailed. However it is understood that the invention includes variations within the scope of the claims which follow.

I claim:

1. A process for making soap which comprises saponifying a mixture of lower alkyl esters of

5 higher fatty acids and an aqueous soap solution by adding caustic alkali to said mixture in several successive stages at temperatures between about 100° C. and about 120° C. under autogenous pressure and continued agitation, adding to the resulting, hot, saponification product a cool, dilute, aqueous solution of an electrolyte, thereby reducing the temperature of the resultant mixture to about 85° C., permitting said mixture to settle at atmospheric pressure, and then separating the neat soap from the nigre therein.

10 2. The process of claim 1 wherein the mixture obtained upon addition of the electrolyte solution to the saponification product contains about 55% by weight of fatty acids combined in the form of soap.

15 3. The process of claim 1 wherein the esters are preheated by heat exchange with the saponifying material.

20 4. The process of claim 1 wherein the soap solution is the neat soap obtained by fitting the nigre from the settling operation.
